UNITED STATES PATENT OFFICE.

GEORGE A. MEAD AND WILLARD H. KEMPTON, OF MANSFIELD, OHIO, ASSIGNEES
TO THE OHIO BRASS COMPANY, OF MANSFIELD, OHIO, A CORPORATION OF NEW
JERSEY.

STRAIN-INSULATOR.

Specification of Letters Patent. Patented Dec. 9, 1913.

Application filed July 13, 1910. Serial No. 571,778.

To all whom it may concern:

Be it known that we, GEORGE A. MEAD and WILLARD H. KEMPTON, both citizens of the United States, residing at Mansfield, in the county of Richland and State of Ohio, have invented certain new and useful Improvements in Strain-Insulators, of which the following is a specification.

This invention relates to improvements for insulating electric wires or cables, and has for its primary object to provide an improved construction, combination and arrangement of parts in strain insulators, such as are employed in railway and power systems for electrically insulating guy, anchor, span, suspension, and conductor wires or cables from poles, bridges, or other structures from which they may be suspended, or in any other place where they may be of service.

Another object is to provide an improved insulator of this type, of simple, durable construction, which can be efficiently used in high tension electric service, and in places where great mechanical strains and stresses are to be met with.

Other and further objects will appear in the specification, and be more specifically pointed out in the appended claims, reference being had to the drawings exemplifying the invention, and in which—

Figure 1 is a side view of an insulator constructed in accordance with the principles of this invention, parts being cut away to show the internal construction of the same. Fig. 2 is a section on the line II—II of Fig. 1. Fig. 3 is a plan view of the sectional ring to be hereinafter referred to.

Referring more specifically to the drawings, a shell 1 is constructed of any suitable metal, and open at both ends. At each end of the shell 1 is an annular enlargement 2 provided with an interior groove 3 extending entirely around said shell and thus providing an annular shoulder or flange 4 projecting inwardly.

A strain member projects from each end of the shell 1, said strain member being embedded in a mass of any suitable cement 5, such as neat Portland cement. Previously to being inserted into the shell 1, each strain member is constructed and assembled as follows: An eye piece 6, preferably of malleable iron, is threaded to the end of a long bolt 7, provided with a bolt head 8 impinging

upon a washer 9, preferably of malleable iron, said washer having been placed upon the bolt 7 before it is passed through a corrugated bushing 10 which is also preferably constructed of porcelain. Said bushing 10 has an enlargement 11 on its inner end, thus forming a contracted neck portion 12. Interposed between the enlargement 11 and the washer 9 is a soft metal washer 13, preferably of lead. If desired, however, parts 8, 9 and 13 may be made of one integral structure secured to the inner end of the bolt 7. The parts 6, 7, 8, 9, 10 and 13 having been assembled, a cup 15, preferably of porcelain, is cemented over the head of the strain member with an insulating cement. After this cement has set, both of the strain members are inserted in the manner already referred to in the shell 1, with the mass 5 of cement between them, said cement 5, as the strain members are shifted inwardly toward each other being crowded outwardly toward the ends of the shell 1 until the parts occupy the relative positions shown in Fig. 1.

Referring more especially to Figs. 2 and 3, suitable means for holding or locking the strain members within the shell 1 is preferably provided by a locking ring constructed in a plurality of sections, said ring being constructed in the present embodiment in two parts 16 and 17. This sectional ring may be held or locked with the ends of the shell by any suitable means, such as by screw-threaded connections, but preferably each section is provided with a plurality of annular lugs or segments 18, which are adapted when the sections of said ring are moved axially into the shell 1 to pass through the segmental recesses 19 formed in the flange 4 until they are brought opposite the annular recesses 3 in the enlarged end portion 2 of the shell 1. Said sections may then be revolved a few degrees about the axis of the shell 1 into the position indicated in Figs. 1 and 2, in which they positively lock the tension members within the shell 1. These operations are of course performed before the cement sets in the outer end of the shell 1, so that after the cement sets, the strain insulator comprises a plurality of rigidly connected parts in the form shown. In order to facilitate the introduction of the tension members into the ends of the shell 1, and to permit an adjustment in the size of the end openings of the shell to 110

make an efficient connection between the ring sections 16 and 17, and the shoulder 4, the outer ends of the shell 1 are slotted, as shown at 20 and 21, thereby making the openings 5 adjustable. Adjacent the slots 20 and 21, the ends of the shell are provided with cheeks or lugs 22, which may be drawn together by bolts 23, or other suitable fastening means.

What we claim is:

- 10 1. A strain insulator comprising an integral shell with expandible open ends and provided with a plurality of inwardly projecting segmental lugs and an internal annular recess inside of the lugs in each of said end openings, an insulating block with an enlarged inner end projecting through each of said end openings into said shell, said blocks being provided with means for attaching cables or supports thereto, and a locking ring with outwardly projecting segmental lugs adapted to be inserted beneath said lugs on the shell at each end to lock said insulating block in position.
- 15 2. A strain insulator comprising an integral shell open at both ends, each of said open ends being slotted to make them adjustable in size, an insulating block protruding from each end, a locking ring between the shell and the block, said blocks being provided with means for attaching a support thereto, and means for contracting the slotted ends to clamp the insulating blocks thereon.
- 20 3. A strain insulator comprising an integral shell open at both ends, each of said

open ends being provided with inwardly projecting lugs arranged at intervals around the inside of said open ends, an insulating block mounted in each end of said shell, said blocks being provided each with an annular 40 shoulder within the shell of a size to be inserted between the lugs, and a locking ring mounted within each open end and in abutment with the shoulder on said insulating block, each of said rings being provided with 45 outwardly projecting segmental lugs adapted to be passed through the spaces between the lugs on the shell and to be rotated under the last said lugs, and means for rigidly securing the several parts together. 50

4. A strain insulator comprising an integral shell provided with a contractible end portion, an insulating block having an end portion of smaller diameter than said shell, said reduced end portion being provided with 55 a neck forming a shoulder, means inter-engaging between the shoulder formed by said neck and said contractible portion of the shell, and a member projecting from said block for engaging a conductor, support or 60 the like.

In testimony whereof we have signed our names to this specification, in the presence of two subscribing witnesses, on this 9th day of July A. D. 1910.

GEORGE A. MEAD.

WILLARD H. KEMPTON.
